(57) **CLAIM**

The ornamental design for a computer cabinet, as shown and described.

DESCRIPTION

FIG. 1 is a front perspective view of a computer cabinet showing a new design;

FIG. 2 is a rear perspective view thereof; and,
FIG. 3 is a side perspective view thereof, the other side being a mirror image.

The areas shown in broken lines are environmental and form no part of the claimed design.

1 Claim, 3 Drawing Sheets

FIG. 1

FIG. 2

FIG. 3
